UNITED STATES PATENT OFFICE.

GEORGE SAMUEL BAKER AND WILLIAM KING BAKER, OF WILLESDEN,
ENGLAND.

MACHINE FOR COVERING SMALL ARTICLES WITH LIQUID OR SEMIQUID COATING.

SPECIFICATION forming part of Letters Patent No. 622,102, dated March 28, 1899.

Application filed November 9, 1898. Serial No. 695,973. (No model.)

To all whom it may concern:

Be it known that we, GEORGE SAMUEL BAKER and WILLIAM KING BAKER, subjects of the Queen of England, residing at Willesden, England, have invented certain new and useful Improvements in Coating-Machines, of which the following is a specification.

This invention relates to machines for covering small articles with a liquid or semi-liquid coating; and it is particularly adapted for applying to confectionery a liquid or semi-liquid coating.

In the accompanying drawings, Figure 1 is a side view of a machine constructed according to this invention. Fig. 2 is a view of the opposite side of the machine. Fig. 3 is an end view of the machine. Fig. 4 is a view similar to Fig. 2 with certain of the parts removed and with the remaining parts in a position different from that in which they are shown in the former figure. Figs. 5, 6, 7, 8, 9, 10, and 11 show successive positions of the arms C, hereinafter referred to, and of the gear by which they are operated. Fig. 12 is a view of the parts shown in Figs. 5 to 11, viewed in a direction at right angles to that in which those figures are viewed. Fig. 13 is a half plan and half horizontal section of parts of the machine, other parts, including the gearing for operating the arms C, being omitted. Fig. 14 is a detail of a bearing for the arms C, hereinafter referred to. Fig. 15 is a detail vertical sectional view, somewhat enlarged, showing more clearly the relative arrangement of the parts D⁶, D⁷, D⁸, D⁹, E², and E³.

Like letters indicate like parts throughout the drawings.

The machine is provided with a tank or box A, containing the coating material. This tank or box is jacketed, a heating medium being introduced into the jacket to keep the coating material in the tank in the liquid or semiliquid state at the desired temperature.

Attached to the sides of the tank A are frames B, in which bearing-blocks B' B² reciprocate vertically. C are arms which are pivotally connected with said blocks B' B². Upon the frames B are mounted segment-racks C' and a gear-train C² C³ for giving vertical motion to the blocks B' B².

C⁴ is a lifting-rod operated by a cam G⁹ and operatively connected with the segment-rack C'

Upon a feed-table D is mounted a hopper D', said table and hopper being adapted to be given a rapid vibratory motion by means of eccentrics D² on a main driving-shaft G and rocking arms D³ D⁴. Into the hopper the small goods to be coated are delivered. If these goods are hemispherical it is necessary that each one should lie on its bottom or flat side when it issues to the coating apparatus. We have found that when a series of such hemispherical blanks is placed indiscriminately on a flat surface shaken horizontally each hemisphere which may have presented its flat side upward is caused to turn over onto that flat surface. Thereafter they can be easily and uniformly fed to the coating apparatus.

The hopper D' has a flat bottom for receiving the hemispheres to be coated, and at the side presented toward the remainder of the machine we provide a chamber D⁵ of a size just sufficient to receive one row of hemispheres. The two walls of this chamber are provided with doors D⁶ D⁷, adapted to be moved vertically and so operated that when the outer door D⁷ is closed to the feed-table the inner door D⁶, admitting the hemispheres from the hopper to the chamber D⁵, is open. When a row of hemispheres has been shaken into this chamber D⁵ by vibration of the hopper, the door D⁶ is closed, and at the same time the door D⁷ is opened by the means presently described, allowing the hemispheres to pass onward to the feed-table, which in this part has diverging grooves, down which the hemispheres or other goods or blanks pass by reason of the shaking motion of the table and hopper aforesaid and are deposited upon a second table D⁸, which is constructed as a grid. The hemispheres are delivered by these grooves onto the grid at the correct distance apart for being carried to a dipping-grid E² by means of a pusher D⁹, connected by a rod to one end of a lever D¹¹, which latter is operated by a cam D¹⁰, secured on a shaft D¹².

The shaft D¹² is driven by means of chain-gearing from the shaft G² and has keyed upon it another cam D¹³, which imparts motion to

the shutter-doors D⁶ D⁷ of the chamber D⁵. These doors or shutters are worked in conjunction the one with the other and so controlled that they give a feed of one series of hemispherical or other goods for each cycle of the operations hereinafter described and controlled by the cam-shaft G².

As shown in Fig. 1, the door D⁷ is raised and the door D⁶ is lowered. Now when during the rotation of the cam D¹³ the projecting or cam portion thereof rides beneath the lower end of the vertical rod D¹⁶, which at its upper end is connected with one end of a rock-lever D¹⁷, to which the doors D⁶ D⁷ are connected, said rock-lever D¹⁷ will be rocked so as to lower the door D⁷ and raise the door D⁶, and as the cam portion of the cam clears the lower end of the rod D¹⁶ the spring D¹⁸ forces the latter down again, thus again raising door D⁷ and lowering door D⁶, and the described reverse movements of the doors are effected at each rotation of the cam D¹³.

E are a pair of arms pivoted at E' on the side frames and connected together at the opposite end by the cross-bar E³, supporting the grid-table E², upon which the hemispheres are pushed from the fixed intermediate table D⁸. When so deposited in place, they are ready to descend into the liquid in the tank A. The grid-table E² is forced down into the liquid by the arms C in their circular passage, presently described, through it. In this circular movement the free ends of the arms C come first into contact with the upper side of the table E²; but in consequence of the frame E E³, which carries the grid-table, having a longer swing or leverage, at about the time when the fingers F², presently described, have seized the hemispheres and have left the liquid the arms C free the table E², and the latter is thus released and allowed to return to its original position by any suitable means, as a spring d⁹, bearing at one end upon the under side of the grid E² and secured at the opposite end to a wall of the tank A, the said grid being then ready to receive the next row of goods to be deposited upon it.

The arms C C are pivotally mounted at one end in blocks B' and B², which slide in vertical guide-openings in the side frames B B. These arms C form a frame having two distinct motions, one a vertical motion in the frame guides, as before stated, and the other a rotary motion on the trunnions in the blocks B' and B². The arms are connected together by a bar F, cast with them.

Upon a bar F⁶, movable in a direction transverse to its length in jaws at the ends of the arms C, are a series of short arms F', set at the same distance apart as the hemispheres when the latter are in position on the table E² ready for dipping. At the extreme end of these short arms is a device (shown in Figs. 3, 4, 5, 6, 7, 8, 9, 10, 11, and 13) comprising fingers F² for gripping the hemispheres when passing through the liquid and releasing them at the proper time described. This

device may be likened to the action of the digits of the human hand and consists of three members, the front one, F⁷, rigidly secured to the end of the short arm F' and which will answer to the thumb and the back ones, F⁸ F⁹, corresponding to the fore and middle fingers, being pivoted to the arm F' and each having a tailpiece F¹⁰. The fingers F⁸ F⁹ are free to move toward or recede from the fixed or thumb piece, as required, in the following manner: Above and below the tail-pieces F¹⁰ of the fingers F⁸ F⁹ rods F³ and F⁴ pass, the ends of which are secured in one of the arms of bell-crank levers F⁵, Fig. 2, pivoted to a continuation of the arm C. The other arm of this bell-crank is adapted to be operated by a guide M M', over which it travels and which operates it to raise or lower the rods F³ and F⁴, and so through the tail-pieces of the fingers causes all the said fingers to move in unison relatively to the fixed pieces F⁷. When the bell-crank F⁵ is not acted upon by the guide-strip M or the incline M', it is influenced by a spring, which has the tendency to cause the fingers to close together, as hereinafter described.

Beneath the tank are suitable shafts for gearing down the speed from the shaft G, carrying the driving-pulleys, to the shaft G², carrying the cams for actuating the several moving parts. In the arrangement shown we employ three shafts G, G', and G². Shaft G carries the driving-pulleys G³, a beveled friction-wheel G⁴ for driving the decorating device, to be hereinafter described, the first pinion of the gearing-down train of spur-wheels G⁵, and eccentrics D² for giving the shaking motion to the feed-table D. Shaft G' is simply an intermediate shaft carrying spur-wheel and pinion G⁶ and G⁷. The shaft G² carries the wheel G⁸, the last of the gearing-down train, and which causes the shaft G² to run at a suitable speed to perform the various operations. The shaft G² carries at one end outside the frames a cam G⁹, whose function it is to raise the blocks B' B², in which the arms C are trunnioned, the blocks and arms descending by their own weight. The other end of the shaft G carries a closed or other suitable cam G¹⁰ for raising and lowering the rack G¹¹ in order to give, in part directly and in part through a pinion H² and other racks H and H', a revolving motion to the frame constituted by the arms C and bar F and hereinafter referred to as the "frame" C C F. The cam G⁹ for giving a vertical motion to this frame operates as follows: A sliding connecting-rod C⁴, upon the lower end of which is a roller resting upon the cam, is connected at the top to a toothed quadrant C'. This quadrant meshes with a pinion C³. The pinion is keyed to a cross-shaft C⁵, upon which are also keyed two spur-wheels C² C², which gear into the racks B³, formed into guide-rods attached to the blocks B' and B². It is only necessary for the cam to lift the frame, the weight of the several parts being sufficient to effect its

descent. By this arrangement a small lifting motion of the cam is multiplied, so as to give the required travel to the sliding blocks B' and B².

5 The closed cam G¹⁰ for giving and governing the rotary motion of the arms C and bar F does so by racks G¹¹, H, and H', of which G¹¹ is under the immediate control of the cam G¹⁰, H is raised and lowered through an idle spur-pinion H², fixed to the top of the side frame, and H' has no motion, but is attached to the side of the machine. On one side of the frame C C F the trunnion carrying it is prolonged, and keyed to it are two pinion-segments side by side. The teeth of these pinion-segments are so arranged that certain blank spaces are left, so as to pass clear of the teeth in the racks when the frame C C F is not required to revolve. One rotary movement of the frame is given by the motion of the rack G¹¹ acting direct upon the pinion-segment H³ while the frame and pinion are not being moved by the cam G⁹. Another portion of this rotary movement is given by the rack H also while the frame is not being moved up and down by the said cam, and the third part of the rotary movement is caused by the downward motion of the frame when the teeth of the pinion-segment H⁴ are engaged 30 with fixed rack H'.

The device for decorating is seen in Figs. 1, 2, 3, and 13. Upright spindles J and J' are mounted in suitable bearings on the side of the tank A and driven during a small portion 35 of the time necessary to perform one operation of coating. These spindles are driven by beveled wheels from the quick-running main shaft G. Of these beveled wheels the pair J² and G⁴ are friction-wheels. The others, Fig. 3, J³, J⁴, J⁵, and J⁶ are ordinary beveled-toothed wheels. Upon the upright spindle J a disk J⁷ is keyed, which has one lug j⁷ on its edge. A sliding bolt J⁸ engages with this lug and prevents the spindle from turning during 45 part of the cycle. During this time one friction-wheel slips past the other. At the proper time of the revolution of the shaft G² a lug or pin J⁹ on cam G¹⁰ draws this bolt aside and the spindle is allowed to revolve. The bolt 50 is released by the onward travel of the cam and returned by an opposing spring j⁹, again holding the spindle from turning. At the top of upright shafts J and J' are horizontal cranks J¹⁰ J¹⁰, Fig. 13, carrying a bar J¹¹. Upon this bar are pins J¹², which engage in 55 the bar F⁶, carrying the finger-arms, and through the cranks motion is given to the finger-bar and fingers. In the example illustrated the bar F⁶ and all the parts attached 60 to it will move in circles of the same size as that described by the pin J¹² on the bar J¹¹, and the residual liquid dropping from between the "thumb" F⁷ and fingers F⁸ and F⁹ will be caused to follow a similar circular path, so as to descend in a circular pattern 65 onto the goods.

At certain stages of the operation a ham-

mering motion may be given to the arms C to knock off the superfluous liquid. No device for this purpose is shown in the drawings. 70

K is a mixer of a suitable form continually revolving in the liquid in the tank A for the purpose of agitating it and keeping it thoroughly mixed.

Fig. 14 shows the device for holding the frame C C F in a horizontal position to right and left of the center of the machine when the pinion-segment teeth are free from the racks. A stop-piece L engages in the depressions in the trunnions of the frame and is 80 held by a spring, as shown.

The operation of coating is as follows: A row of small goods being automatically placed upon the dipping-grid E², Fig. 1, the fingers F⁷ F⁸ F⁹ descend and hold them, as shown in 85 Fig. 5. The cam G¹⁰ moves in the direction of the arrow, causing the teeth on rack G¹¹ to ascend and to revolve by means of the pinion H³, the frame C C F carrying the fingers F⁷ F⁸ F⁹ and the goods retained in them 90 backward and forward in the liquid in the tank A, finally stopping in the position shown in Fig. 6, where the superfluous coating material may be knocked off by a mechanical hammer or otherwise. Cam G⁹ now by acting 95 on the parts C⁴ C' C² C³ B³ B' B² raises the frame vertically to position shown in Fig. 7, when the pinion H³ engages in rack H, which here has no motion. Its further vertical travel causes it to revolve, landing it upon a 100 table in position shown in Fig. 8, at which moment the fingers are caused to open and release the goods, and then being still further lifted vertically without rotation the fingers are caused to close, as in Fig. 9. As a 105 certain amount of residual liquid adheres to the fingers, which are now joined together, it runs in a stream from them, and at this moment the decorating device being set in motion by friction-gear device an ornament is 110 made on the top of the goods. Rack H now rises under the action of parts G¹⁰ G¹¹ H², giving the finger-frame C C F a half-turn in the opposite direction. The whole frame now 115 descends vertically, when the finger-frame assumes the position shown in Fig. 11 through the action of the outer pinion H⁴, Fig. 12, engaging with the fixed rack H'. At the same time the fingers are opened by means of bell-crank F⁵ coming in contact with the guide-strip M, as shown in Fig. 1. The fingers are now immediately over another row of goods which have meanwhile been deposited upon the dipping-grid, and the further downward vertical descent of the frame causes the fingers 125 to take hold of the new row of goods and the operation is repeated.

It is clear that by giving various movements to the finger-bar F⁶ circles, straight lines, wavy lines, or any other required design can be given to the tails for the ornamentation of the top of the goods by means of modified and suitable gearing attached to the top of the vertical shaft J and J.

- What we claim, and desire to secure by Letters Patent, is—
1. In a machine of the character described, the combination with a support for the articles to be coated, and a receptacle for coating material, of means for depressing said support within said receptacle, seizing the articles and removing them from their support after being coated, comprising fingers adapted to close upon the articles simultaneously and similarly release them, and means for operating the fingers.
  2. In a machine of the character described, the combination with a pivoted support for the articles to be coated, and a receptacle for coating material, of means for depressing said support within the receptacle and seizing the articles and removing them from their support after being coated, comprising pivoted arms, fingers carried thereby adapted to simultaneously close upon the articles and simultaneously release them, and means for operating the fingers.
  3. In a machine of the character described, the combination with a pivoted support for the articles to be coated, and a receptacle for coating material, of means for depressing said support within the receptacle, seizing the articles and removing them from their support after being coated comprising pivoted arms, fingers carried thereby, means for operating the fingers to cause them to simultaneously seize and similarly release the articles, and means for imparting forward and backward swinging movements to the arms and fingers and the articles held thereby within the material in the receptacle.
  4. In an apparatus of the character described, the combination with a support for the articles to be coated and a receptacle for coating material, of devices for depressing said support within said receptacle and seizing the articles and removing them from their support after being coated and delivering them exteriorly of the receptacle, and means for imparting a motion to said delivery devices after having released the coated articles, while in a position directly over said articles for the purpose set forth.
  5. In an apparatus of the character described, the combination with a receptacle for coating material, of guideways, vertically-movable blocks therein, arms pivotally connected at one end with the blocks, and adapted for vertical movement therewith, gripping devices carried by the arms and means for imparting swinging movements to the arms as the latter and the blocks move vertically in the guideways, in the manner and for the purposes specified.

6. In an apparatus of the character described, the combination with a receptacle for coating material, of guideways, vertically-movable blocks therein, connected arms pivotally connected at one end with the blocks, and adapted for vertical movement therewith, a pinion mounted upon the trunnion of one of the arms, the racks G^{11} , H and H' with which said pinion is adapted to engage, means for moving the rack G^{11} vertically, and gripping devices carried by the arms, all arranged and adapted for coöperation as and for the purposes specified.
7. In a machine of the character described, the combination with a receptacle for coating material, of a grid adapted to receive the articles to be coated, pivoted arms supporting said grid, pivoted arms adapted for vertical as well as swinging movements, gripping devices carried by the latter arms and corresponding to the divisions of the grid and adapted to seize the articles on said divisions and remove them from the grid, means for operating the gripping devices, and means for operating the pivoted arms carrying the said gripping devices.
8. In a machine of the character described, the combination with a receptacle for coating material, of a receptacle for the articles to be coated adapted to be given a vibratory motion, a grid arranged to receive the articles as they are delivered from said latter receptacle, and a second grid arranged to receive the articles from the first grid, means for pushing the articles from the first grid onto the second grid, and means for seizing the articles from the second grid and passing them through the coating material.
9. In an apparatus of the character described, the combination with a receptacle for coating material, of guideways, vertically-movable blocks therein, connected arms pivotally connected at one end with the blocks and adapted for vertical movement therewith, a pinion mounted on the trunnion of one of the arms, racks G^{11} , H and H' with which said pinion is adapted to engage, gripping devices carried by the arms, racks B^3 carried by the blocks, pivoted quadrant-racks, and gearing between the latter racks and the racks B^3 , and means for oscillating the quadrant-racks.

In testimony whereof we have hereto set our hands in the presence of the two subscribing witnesses.

GEORGE SAMUEL BAKER.
WILLIAM KING BAKER.
